UNITED STATES PATENT OFFICE.

ALBERT F. MILLER, OF NEW YORK, N. Y., ASSIGNOR TO INDIVIDUAL SPECIALTIES, INC., OF NEW YORK, N. Y., A CORPORATION OF NEW YORK.

PEG-BOARD.

1,221,470.

Specification of Letters Patent.

Patented Apr. 3, 1917.

Application filed December 30, 1915. Serial No. 69,309.

To all whom it may concern:

Be it known that I, ALBERT F. MILLER, a citizen of the United States, and a resident of the city, county, and State of New York, have invented a certain new and useful Improvement in Peg-Boards, of which the following is a specification.

This invention relates to a type of sign board or directory generally found in hotels, clubs, office buildings and the like, wherein a series of signs generally detachable are displayed on the sign board, being the names of the occupants of the building.

The objects of my invention are to provide an article of this class consisting of a frame whereon a series of detachable signs bearing the names of the occupants of a building, are displayed. Each of these signs or name plates are readily detachable from the main frame and are so arranged that one may be removed without disturbing the position of the others, which is a very apparent advantage over the devices in use at the present time wherein a number of the name plates or signs have to be removed or shifted to either remove or shift the position of one of them. My invention also provides means whereby suitable objects may be secured adjacent the name plates of an occupant indicating whether said occupant is in or out of the building or that there is mail for said occupant so that he can call for the same.

These and other objects are accomplished by my invention, a more particular description of which will appear below.

Reference is to be had to the accompanying drawings, forming part hereof, in which—

Figure 1 is a front elevation of my improved peg board;

Fig. 2 is an enlarged front elevation of a section of the same;

Fig. 3 is a sectional view on the line 3—3 of Fig. 2;

Fig. 4 is a vertical sectional view of a portion of the board;

Fig. 5 is an end elevation of one of the name plates;

Fig. 6 is a sectional view of a modified form of board;

Fig. 7 is a perspective view of a modified form of post to which the name plates are attached;

Fig. 8 is a sectional view of a modified

form of upright used in the frame construction;

Fig. 9 is a front elevation of a modified form of name or letter plate;

Fig. 10 is a perspective view of a peg;

Fig. 11 is a perspective view of a tool or implement used to remove the name plates from the board.

Throughout the various views of the drawings, similar reference characters designate corresponding parts.

As above mentioned, my improved peg board may be used in buildings, clubs, hotels and the like, but I do not limit my invention to use in this manner, as it may be readily and appropriately used for score boards, bulletin boards and the like.

My improved peg board comprises a frame of any desired form having a top 1, bottom 2, and rear wall 3. Extending from the top of the frame to the bottom and secured to the rear wall 3 by bolts or like fastening means 4, are a plurality of uprights 5. Situated intermediate of these uprights, are vertical posts 6, these posts being secured to the rear wall 3 by bolts 7, which pass through spacing blocks 8, which blocks retain the posts a suitable distance from the rear wall without interfering with the action of the name plate clips which will be described below.

Secured to the outer face of the uprights 5, by the bolts 4, are the vertical plates 9, each of said plates having a plurality of perforations 10 therein. The plates 9 are not as wide as the uprights 5, whereby the ends of the uprights project slightly over the ends of the plates 9 forming shoulders 11 upon which the ends of the name plates rest.

The name or letter plates 12 are preferably formed of a single piece of material and consist of a rear plate 13, the edges, with the exception of one of the same, being turned over or flanged as at 14, which flanges retain the card 15 bearing the lettering, in place. As above mentioned, one of the edges is not flanged so that the card may be readily slipped in place. If desired, a strip of glass or like transparent material 16 may be placed in front of the card 15 and inclosed by the flanges 14.

To form the clip or retaining means for the name plates, the rear plate 13 has two

stamped out portions 17, and the metal contained within said portions is bent back to form a pair of arms 18, which arms are resilient and bent to frictionally engage the 5 posts 6 between them.

From the foregoing, the operation of my improved peg board will be readily understood. The name plates 12 are held on the posts 6 by the two arms 18 which form what 10 can be termed clips, and these name plates can be moved up or down to any desired position on the board. The outer ends of the name plates rest on the shoulders 11 preventing a twisting or turning of the name 15 plates on the posts 6, and as Fig. 3 will show, the surface of the name plates and uprights presenting a practically flush appearance. To remove one of the name plates without disturbing the positions of the 20 others, I provide a tool or implement such as shown in Fig. 11, which has a handle portion and flanges 20 on its ends, these flanges being bent reversely or in opposite directions to one another so that they can be slid under the upper and lower flanges 14 on the name plates and a slight outward pull 25 draws the arms 18 out of engagement with the posts 6 so that the name plates 12 can be readily removed.

30 In Fig. 10 is shown a peg 21, having a shank 22 adapted to enter the perforations 10 in the upright plates 9. If desired, these pegs may be of varying colors and when placed in the perforations adjacent the 35 name of a person on the name plate may serve to indicate that that person is in the building. The position of the perforations may also serve to indicate various things, that is, a certain colored peg placed in a 40 certain perforation adjacent the name plate bearing a person's name may tend to indicate the arrival of mail for him.

It will be noted, from the above, that this device is applicable to a varying 45 amount of uses.

50 In Fig. 6 is shown a modified structure wherein the name plate is of greater length than that shown in Figs. 1, 2, and 3, and instead of a single post 6 being placed intermediate of the uprights 5, a pair of posts is used and two pairs of arms 18 are formed on the back of the name plates to engage 55 said posts.

55 In Fig. 7, I have shown a modified form of posts 6, which consists of a plate 23, provided with perforations 24 for the reception of screws or like securing means for attaching the same to the rear wall 3. A narrow web 25 unites the plate 23 with 60 the post 26, which is made substantially circular in cross section or of a configuration adapted to fit between and frictionally engage the resilient arms 18 on the name plate.

65 In Fig. 8, is shown a modified form of upright which consists of a combination of

the upright 5 and plate 9 from a single section of flat material which is bent to form projections on its sides, the outer faces of which form shoulders 28 against which the ends of the name plates may bear.

70 In Fig. 9 is shown a modified form of name plates constructed in the same manner as above mentioned, except that it is of slightly different shape or outline and is applicable for use in connection with score 75 boards and the like.

75 From the foregoing, it is obvious that my invention is not to be restricted to the exact embodiment herein shown and described, but is broad enough to cover all structures 80 coming within the scope of the annexed claims.

Having described my invention, what I claim is:

1. A peg board comprising a frame, a 85 series of name plates, a ledge formed on the edge of said frame, resilient clips on the name plates and means within the frame for detachably engaging the clips and holding the name plates within the frame and 90 against the ledge.

2. A peg board comprising a frame, a series of posts in said frame, a plurality of name plates, means for detachably securing said plates to said posts and a plurality of 95 perforations on said frame for the reception of pegs.

3. A peg board comprising a frame, a series of upright posts within said frame, a plurality of name plates, means on said 100 name plates for detachably securing them to the posts and a plurality of perforations in the frame for the reception of plugs adjacent the ends of the name plates.

4. A peg board comprising a frame, a 105 series of braces within said frame, posts secured in said frame, a plurality of name plates or signs and means on said name plates for detachably securing the same to the posts.

5. A peg board comprising a frame, a series of uprights within said frame, posts secured in the frame, a plurality of name plates for detachably securing the same to the posts and a plurality of perforations in 115 the uprights for the reception of pegs.

6. A peg board comprising a frame, a series of uprights secured within said frame, posts secured within said frame and intermediate said uprights, a plurality of name 120 plates, clips on said name plates for detachably securing the same to the posts and shoulders on said uprights against which the name plates bear when secured to the posts.

7. A peg board comprising a frame, a series of uprights secured within said frame, posts secured within said frame, a plurality of name plates, resilient arms at the rear 125 of said name plates and adapted to detach-

ably frictionally engage said posts and a series of perforations in said uprights.

8. A peg board comprising a frame, a series of uprights within said frame, shoulders formed on said uprights, a plurality of posts in said frame and intermediate said uprights, a plurality of independent name plates having spring arms at their rear sides, said arms adapted to embrace and 5 detachably secure the name plates to the posts, portions of said name plates, adjacent their ends, adapted to bear against the shoulders on the uprights.

9. A peg board comprising a frame, a series of uprights within said frame, perforated plates secured to said uprights, a series of posts secured within said frame, a plurality of independent name plates or signs having resilient arms formed from metal stamped out of the rear wall of said name plates, said arms detachably embracing the posts. 15 20

Signed at the city, county and State of New York, this 23rd day of November, 1915.

ALBERT F. MILLER.
